UNITED STATES PATENT OFFICE.

HARRY H. DODGE, OF BUFFALO, NEW YORK.

FURNACE.

Application filed October 30, 1923. Serial No. 671,786.

To all whom it may concern:

Be it known that I, HARRY H. DODGE, a citizen of the United States, and a resident of Buffalo, in the county of Erie and State of New York, have invented certain new and useful Improvements in a Furnace, of which the following is a full, clear, and exact description.

This invention appertains to certain improvements in furnaces generally, and more particularly to a type of the same adapted for use in the metallurgical or enamelware making industries and the like, wherein extremely high and uniform temperatures are essential to the production of perfectly finished articles of manufacture.

In the prior practice of design and operation of furnaces, particularly in the enamelware industry, serious disadvantages, difficulties and much trouble has been experienced in the production of high grade enamelware, both with regard to the quality or perfection of finish to the articles as well as to keeping the cost of manufacture at a reasonable figure. The more important of these several disadvantages, difficulties and troubles, are: first, the high cost of fuel consumption of a furnace per pound weight of the articles produced; second, the inability to maintain a constant or maximum temperature within the furnace, especially during the loading and unloading periods of operation thereof; third, the inability to maintain uniform temperature throughout the interior of the furnace, particularly at or along the hearth thereof; and, fourth, the inability to obtain low velocities in the products of combustion, such as otherwise act on the molten enamel coating on the articles being fired to keep the same in motion in the early stages of the firing operation and frequently result in a lumpy appearance in the finished surfaces of the articles.

The principal object of the present invention therefore is to provide for a furnace construction, wherein the articles to be fired are subjected to direct contact with the products of combustion thereof, such as will readily and efficiently overcome the several difficulties, disadvantages and troubles, aforesaid, and which will admit of the production of smooth finished enamel coatings, free from any and all blemishes or lumpy effects either in appearance or in fact.

Another object of the invention is to pro-

vide for a furnace of the class mentioned, and one wherein the hot products of combustion will be evenly distributed so that a uniform temperature will be maintained throughout the interior of the furnace, and much higher temperatures will be possible with a marked reduction in fuel consumption and consequently in the cost of operation.

A further object of the invention is to provide for a furnace of the character described, and one wherein the usual stack for the exhaust of the products of combustion from the interior of the furnace will be dispensed with, such as will result in higher temperature being produced and maintained within the furnace, the products of combustion will be practically stagnant or of extreme low velocity during the firing periods of operation, and the desired high temperatures will be quickly restored within the furnace after each loading and unloading period thereof.

A further object of the invention is to provide for a furnace of the type set forth, and one of an extremely simplified construction and arrangement, such as will involve a much lower cost in materials, labor and time in its manufacture and installation and in maintenance and operation as compared with that of these types of furnaces now employed in the practice.

With the foregoing and other equally important objects in view, the invention resides in the certain new and useful construction and arrangement of parts as will be hereinafter more fully described, set forth in the appended claims, and illustrated in the accompanying drawings, in which:

Figure 1 is a fragmentary front elevation, partly in section, of a preferred embodiment of the furnace,

Figure 2 is a side elevation thereof,

Figure 3 is a vertical transverse section taken on the line 3—3 of Figure 2, and,

Figure 4 is a fragmentary vertical longitudinal section taken on the line 4—4 of Figure 1.

Referring to the drawing, wherein similar characters of reference designate corresponding parts throughout the several views thereof, the preferred embodiment of the furnace comprises a supporting frame consisting of vertically disposed members 10 arranged in spaced relation at the opposite sides of the furnace, similarly disposed and

arranged members 11 at the rear end thereof, and the members 12 at its front end, all of which are formed of an angle or channel iron, preferably U-shaped in cross-section. The frame members 10 at each side of the furnace, and the complementary of the front and rearwardly disposed members 11 and 12, are connected together by means of longitudinal bars of angle iron 13 which are spaced at an equal distance above the ground or floor level, to support thereon the furnace proper, substantially as shown, while the upper ends of the rearwardly disposed members 11 are connected with the front members 12 by means of longitudinal bars of angle iron 14, the latter extending in common plane above and parallel to the lower bars 13 and connecting the front members 12, which are of a greater height than either of the side members 10 or the rear members 11, at joints below their upper ends.

The furnace proper consists of an outer casing, preferably of a heavy sheet metal formed of a bottom wall 15 which is supported on the upper sides of the longitudinal bars 13; oppositely disposed side walls 16 which abut the inner side faces of the oppositely disposed sets of side frame members 10; rear and front end walls 17 and 18 which similarly abut the inner side faces of the rear and front frame members 11 and 12, and a top wall 19 which extends directly beneath the upper longitudinal bars 14.

Disposed within the outer metal casing is a lining of fire brick or the like, which is formed to provide a hearth portion 20 having oppositely disposed side walls 21 rising therefrom with their top edges spaced below the upper edges of the complementary side walls 16 of the outer casing. The lower portions of the side walls 21 are thickened at their inner sides, as at 22, to provide an article receiving space between the opposed vertical walls thereof, and flat upper faces along the outer edges of which are supported baffles 23. Opening through the side walls 21 in a horizontal plane above the upper flat faces of the lower thickened portions 22 are a series of equidistantly spaced twyer or burner openings 24 which are slightly flared in an inward direction in a manner to discharge the flames from the burners 25 inserted in their outer ends directly against the baffles 23, the spaces 23' formed between the latter and the opposed faces of the side walls 21 constituting the combustion chambers for effecting a uniform distribution of the products of combustion from the burners 25 into the central heating portion of the furnace. Formed longitudinally within the lower portions of the side walls 21 are flues 26 which extend from points inwardly of the forward wall of the furnace to and

open through the rear wall thereof. Opening laterally through the thickened portions 22, of the side walls 21, are outlet flues 27 through which the burnt gases or waste products of combustion pass from the interior of the furnace to the main outlet flues 26. The bottom walls of the several flues 26 and 27 are disposed in the plane of the inner surface of the hearth 20, so that the hot gases or products of combustion must traverse the entire interior of the furnace from the upper side thereof to the hearth surface before passing outwardly of the lateral flues 27. Supported on the hearth 20 in spaced parallel relation to the inner vertical walls of the thickened portions 22 of the side walls 21, and consequently to the ends of the lateral flues 27 opening through the latter, are baffles 28 which act to retard the outflow of the hot gases or products of combustion directly to and through the latter. The upper sides of the central heating space and the combustion spaces at the opposite sides thereof are enclosed by an arched top wall 29 which is keyed in proper position by means of angular stretches 30 of the fire brick interposed between the opposed side edges of the top wall 29 and outer stretches 31 of fire brick disposed along the upper edge 95 portions of the side walls 16 of the outer casing of the furnace.

As best shown in Figure 3, an air space 32 may be provided beneath the top wall 19 of the outer casing, and for the purpose 100 of allowing for a circulation of air through this space, the upper edges of the opposite side walls 16, of the outer casing, are spaced below the top wall 19 thereof, and these edges are disposed in the plane of the upper 105 sides of the courses of fire brick 30 and 31, while the highest point on the outer surface of the arched top wall 29 is spaced at a slight distance below the top metal wall 19.

The forward end of the furnace, between 110 the frame members 12 is formed to provide a loading and unloading opening, which is normally closed by a door or closure member 33 mounted for vertical sliding movements in the opposed channelled faces 115 of the frame members 12. In its lowered closed position, the closure member 33 is supported on a cross bar or sill 34 extending between the frame members 12 with its upper face disposed substantially in the 120 plane of the upper surface of the hearth 20.

To facilitate the opening and closing operation of the furnace door or closure member 33, the same is preferably counterweighted for such purpose, and this is accomplished by suspending the door or closure from one end of a cable 35, by means of an eye member 36 carried at a central point on its upper edge, and passing the other or free end of the cable 35 upwardly between 130

the frame members 12, and then training the same laterally over an inner pulley 37, which is journaled in and between a pair of cross bars 38 secured in position at the opposite sides of the upper ends of the frame members, and from thence over a second pulley 39, journaled between the extreme outer ends of the cross-bars 38, which are extended to point slightly beyond one side 5 of the furnace. The free end portion of the cable 35, depending from the outer pulley 39, is now weighted, as at 40, in any suitable or desired manner, and substantially as shown.

15 In the operation of the furnace as thus constructed and arranged and with the hearth 20 loaded in the usual manner with the articles to be heat treated or fired and the burners ignited, the hot products of 20 combustion from the latter are projected inwardly of the flared openings or passages 24 and directly against the baffles 23, where they will be first spread along the combustion chambers or spaces, formed between the 25 opposed vertical faces of the baffles 23 and the side walls 21 of the fire brick lining of the furnace, and to either side of the openings or passages 24, and then deflected in the upward direction to pass over the top edge 30 of the baffles 23, and between the same and the arched top wall 29, and inwardly toward the center of the furnace and from thence downwardly toward the hearth 20, where the waste gases will exhaust outwardly of the 35 transverse and longitudinal flues 27 and 26, passing over the lower baffles 28 from the heating space immediately above the hearth 20 for the purpose. With this arrangement 40 of the combustion chambers or spaces along the inner side walls 21 of the furnace, extremely hot zones are created for the entire length of the same, and the hot products of combustion are uniformly spread and distributed upwardly and inwardly over the 45 top edges of the baffles 23. The hot gases or products of combustion from the opposite sides of the furnace thus meet and commingle together substantially in the plane of the longitudinal center of the upper part of the heating space above the 50 hearth 20, and then pass downwardly toward the latter in combined volume to be finally exhausted outwardly of the transverse and longitudinal flues 27 and 26. By 55 reason of the fact that no stack is to be employed with this furnace, and that the several flues 26 and 27 are disposed immediately at or above the level of the hearth 20, this exhaust of the waste products of 60 combustion will be comparatively slow, since no appreciable draft will be induced in the flues 26 and 27 to accelerate such exhaust, and, consequently, only maximum heating effects will be obtained from the hot gases 65 or products of combustion in their passage

through the furnace from the oppositely disposed side combustion chambers to the flues. Also, when the door or closure member 33 is opened for purposes of loading and unloading articles into and from the interior 70 of the furnace, this lack of draft effects through the flues 26 and 27 tends to prevent any serious admission of cold air through the door opening, so that the reduction of temperature within the furnace is 75 minimized, and the slightly reduced temperature is quickly raised to maximum upon the completion of a loading operation and the closing of the door or closure member. This slowness of exhaust of the waste gases 80 or spent products of combustion, together with the efficient and uniform spreading out and distribution of the hot gases or products of combustion inwardly from the opposite sides of the furnace throughout 85 the entire length thereof, results in the creation within the latter of extremely high and even temperatures with a comparatively low fuel consumption, and, consequently, greatly reduces the cost of operation, as 90 compared to the otherwise excessive costs of operation of the types of furnaces now made use of in the practice; and, also a more perfect and smooth finish is produced on the articles under treatment, by reason of the 95 extremely low velocity of the hot gases or products of combustion in their passage through the furnace, since the molten enamel or other coating on the articles being fired will not be effected thereby, as is the case of 100 the passing of the hot gases or products of combustion therethrough at high velocities, when the molten coating is often disturbed or moved about on the surfaces of the articles in a manner to give to the finished 105 coating, when hardened, a lumpy or wavy and uneven finish.

From the foregoing, it will be readily apparent that, while a preferred embodiment of the furnace has been described and illustrated herein in specific terms and details of construction and arrangement of parts, various changes in and modifications of the same may be resorted to without departing from the spirit of the invention, 110 or the scope of the claims appended hereto.

Having thus fully described the invention, what is claimed, is:—

1. A furnace as characterized, comprising oppositely disposed parallel side walls, a lower flat hearth wall, and an upwardly arched top wall, combustion chambers extending longitudinally of the opposed faces of said walls provided with upright baffle members at their inner ends, said combustion chambers being disposed intermediate said lower hearth and the arched top wall, an outlet flue formed in each side wall beneath said combustion chambers and extending longitudinally through said walls, and a 120
2. A furnace as characterized, comprising oppositely disposed parallel side walls, a lower flat hearth wall, and an upwardly arched top wall, combustion chambers extending longitudinally of the opposed faces of said walls provided with upright baffle members at their inner ends, said combustion chambers being disposed intermediate said lower hearth and the arched top wall, an outlet flue formed in each side wall beneath said combustion chambers and extending longitudinally through said walls, and a 125
3. A furnace as characterized, comprising oppositely disposed parallel side walls, a lower flat hearth wall, and an upwardly arched top wall, combustion chambers extending longitudinally of the opposed faces of said walls provided with upright baffle members at their inner ends, said combustion chambers being disposed intermediate said lower hearth and the arched top wall, an outlet flue formed in each side wall beneath said combustion chambers and extending longitudinally through said walls, and a 130

- plurality of lateral flues opening inward through said walls onto said hearth at points below said combustion chambers and communicating with said outlet flues.
- 5 2. A furnace as characterized, comprising oppositely disposed parallel side walls, a lower flat hearth wall, and an upwardly arched top wall, continuous inwardly thickened lateral portions formed on the lower 10 sides of each side wall full length thereof, continuous vertical baffle members disposed longitudinally of the furnace along the inner edges of said inwardly thickened portions whereby to form with the inner faces 15 of said side walls combustion chambers said
- side walls being provided with burner openings extending transversely therethrough and in communication with said combustion chambers, an outlet flue disposed longitudinally through the side walls in the 20 bottom portions thereof, said bottom portions of said side walls being provided with lateral flues communicating from the interior of the furnace to said outlet flue on the hearth, and vertical baffle members arranged 25 longitudinally in the furnace in front of said lateral flues and on the hearth wall to provide work supporting members.

HARRY H. DODGE.
